UNITED STATES PATENT OFFICE

GEORGE W. HEINTZ, OF HAMILTON, OHIO

DESIGN FOR AN AUTOMOBILE RADIATOR CAP

Application filed September 7, 1928. Serial No. 28,072. Term of patent 3½ years.

To all whom it may concern:

Be it known that I, GEORGE W. HEINTZ, a citizen of the United States, residing on Rural Route #3, Hamilton, in the county of Butler and State of Ohio, have invented a new, original, and ornamental Design for Automobile Radiator Caps, of which the following is a specification, reference being had to the accompanying drawing, forming part thereof.

Fig. 1 is a perspective view; and Fig. 2 a top plan view, representing my invention.

I claim:

The ornamental design for an automobile radiator cap substantially as shown.

GEORGE W. HEINTZ.
